(57) **CLAIM**

We claim the ornamental design for a model vehicle bumper, as shown and described.

DESCRIPTION

FIG. 1 is an upper, right, rear perspective view of a model vehicle bumper;

FIG. 2 is a rear elevation view thereof;

FIG. 3 is a front elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a lower, right, rear perspective environmental use view of the model vehicle bumper.

In the drawings, the broken line showing of features of the model vehicle bumper illustrate portions of the model vehicle bumper that form no part of the claimed design; whereas, the broken line showing of the environmental use view depicts environmental subject matter and is provided for the purposes of illustrating environmental use structure and context and also forms no part of the claimed design.
